UNITED STATES PATENT OFFICE.

PERRY O. LOWERS, OF FREDONIA, KANSAS.

SHADE AND CURTAIN HANGER.

Application filed August 23, 1926. Serial No. 130,951.

This invention relates to new and useful improvements in shade and curtain hangers and has for its primary object to provide a device that may be rigidly secured to the frame of a window, and that is so constructed as to facilitate the hanging of both a shade and curtain.

An additional object of the invention is to provide a device of this character that is readily adjustable to window frames of various widths and that is further so constructed as to permit of the adjustment of the shade holding bracket after the device has been secured to the window.

Other objects will become apparent as the nature of the invention is better understood, the same comprising the novel form, combination and arrangement of parts herein-after more fully described, shown in the accompanying drawings and claimed.

In the drawings wherein like reference characters indicate corresponding parts throughout the various views:

Figure 1 is a fragmentary front elevation of a window equipped with my novel shade and curtain hanger, the curtain hanger being removed.

Figure 2 is a top plan view thereof disclosing the curtain hanger in position.

Figure 3 is an enlarged fragmentary front elevation of the hanger for disclosing more clearly the means for facilitating the longitudinal adjustment of the device so as to permit the association of the same with various widths of window frames.

Figure 4 is a transverse sectional view of the hanger taken substantially upon the line 4-4 of Figure 3 for more clearly disclosing one of the means for facilitating the detachable association with a generally conventional form of curtain rod therewith.

Figure 5 is a similar view taken substantially upon the line 5-5 of Figure 3 for disclosing more clearly one of the shade roller brackets that forms a novel part of the present device.

Figure 6 is a horizontal section taken substantially upon the line 6-6 of Figure 5 for more clearly disclosing the association of said bracket with the hanger as well as the means for permitting of the longitudinal adjustment of the bracket with respect to the hanger, and

Figure 7 is a transverse section taken substantially upon the line 7-7 of Figure 6 for

disclosing more clearly one of the units of the hanger adjustment mechanism.

Now having particular reference to the drawings, my novel device constitutes the provision of a pair of flat like bars 5 and 6 that are slidably interconnected by reason of straps 5' and 6' at the inner ends thereof that overlap the bars opposite to the ones with which they are associated as more clearly disclosed in Figures 2 and 3. The outer ends of these bars are bent inwardly as at 7-7, which inwardly bent portions are formed or provided with biting tines 8 for the purpose of biting into the material comprising the window frame A when said bars are forcibly moved together.

At the inner end of the bar 5 the top edge thereof is toothed as at 9 while slidably arranged upon the toothed portion of this bar is a strap 10, the upper end of which is formed with a slot 11. Arranged for vertical slidable movement upon this strap 10 is a much narrower strap 12 that is formed at its upper end with a depending lip 13 that projects downwardly through the slot 11 in said strap 10. The strap 10 is formed upon its bottom side with a depending extension 14 arranged transversely through which is a pin 15 to one end of which is rigidly secured a small finger lever 16 while the opposite legs of said strap 12 are secured at their lower ends eccentrically to said pin 15 as is disclosed in Figure 7. Obviously, by the swinging of the lever 16 into the position disclosed in Figure 3, the strap 12 will be forced downwardly upon the strap 10 in order that the lip 13 will engage the teeth 9 of the bar 5 so as to prevent the movement of the strap 10 thereon. Opposite movement of the lever will disengage said strap lip from the teeth and permit the free sliding movement of the strap 10 upon said bar.

Pivoted to one side of the bar 6 at the end thereof adjacent the mechanism just described is a finger lever 16' to the extreme lower end of which is pivotally connected a link 17 that is in turn pivotally connected at its opposite end to the strap 10. It will be apparent that after the strap 10 has been released and the bars opened or closed to secure the desired length, it will be first necessary to lock the strap 10 to the bar 5 and then arrange the hanger in proper position upon the window frame.

A movement of the lever 16 in the direc-

tion of the arrow disclosed in Figure 3 will cause the bars 5 and 6 to be further brought together for firmly binding the hanger to the window frame.

5 Rigidly secured to the bars 5 and 6 at their front sides and adjacent their outer ends and in slight spaced relation with the bars are curtain rod brackets 18-18 the upper edges of which are formed with vertical slots 19 so as to facilitate the attachment of the inwardly bent outer ends of a conventional form of adjustable curtain rods 20, which is of generally conventional construction and therefore a specific description of the rod is believed unnecessary.

Directly inwardly of the curtain rod bracket 18 upon each of the bars 5 and 6 the respective bar is formed with a plurality of longitudinally spaced transversely 20 extending slots 21. Mounted for limited longitudinal sliding movement upon each bar within the area of said slots 21 are peculiarly constructed brackets 22, each in the form of a metallic plate, the opposite 25 ends of which are bent over the opposite edges of the respective bar as indicated by the reference characters 23, in Figure 5. The material forming these brackets is bent inwardly and then laterally outwardly 30 to provide a pair of spaced plates 24-24, between which is pivotally disposed a bracket plate 25 that is formed in one instance with an opening, and in another instance with a slot for receiving the usual 35 rounded and flat pintles upon the opposite ends of a conventional spring shade roller as disclosed in Figures 1 and 2.

The inner ends of these brackets 25 are rounded as indicated by the reference 40 character 26, said rounded inner ends extending through slots in the plates forming said brackets 22. As more clearly disclosed in Figure 5, these brackets 25 are eccentrically pivotally connected between the plates 24-24 and by swinging the same upwardly 45 the inner ends of the brackets will be released from the slots 21 in the bars 5 and 6 and consequently the brackets may be longitudinally adjusted upon said bars. Each 50 bracket 25 is formed at its inner end and at its lower edge with a finger 27 for bearing against the particular bracket plate 22 for limiting the downward swinging movement thereof.

55 The pivotal connection between the plates 24-24 and the respective bracket member 25 is in the form of a headed and threaded bolt 28 upon the threaded end of which is a nut 29. Surrounding the bolt between 60 the nut and the adjacent bracket plate 24 is an expansible coil spring 30 for maintaining the plates 24-24 in frictional engagement with the bracket 25 so as to prevent the accidental swinging movement of 65 the same with respect thereto.

It will thus be seen that I have provided a highly novel, simple, and efficient form of combined shade and curtain hanger that is well adapted for all the purposes heretofore designated and even though I have herein 70 shown and described the invention as consisting of certain detail structural elements it is nevertheless to be understood that some changes may be made therein without affecting the spirit and scope of the appended 75 claims.

Having thus described the invention, what I claim as new is:

1. In a combined shade and curtain hanger of the class described, a pair of bars slidably interconnected, means at the outer ends of the bars for biting engagement with the sides of a window frame, means whereby the bars may be initially loosely secured in predetermined adjusted relation, said means comprising a strap member slidable along one of the bars and adapted for locking engagement on the bar in any adjusted position, additional means for drawing the bars inwardly to a predetermined degree so that the outer ends of the bars will bite into the sides of the window frame, and shade brackets arranged on the bars.

2. In a combined shade and curtain hanger a pair of bars slidably interconnected, means at the outer ends of the bars for biting engagement with the sides of the window frame, the upper edge of the one bar being toothed, a strap member slidable along the toothed bar and having a slot formed in the top thereof, an auxiliary strap disposed above the aforementioned strap and eccentrically pivoted at its lower end to the lower end portion of the first mentioned strap, a dog at the top of the auxiliary strap adapted for movement through the slot formed in the top of the first mentioned strap, whereby said dog may engage the teeth on said bar for locking the straps against sliding movement along the bar, whereby the bars will be initially secured in predetermined adjusted relation, secondary means for drawing the bars inwardly to a predetermined degree so that the outer ends of the bars will bite into the sides of the window frame, and shade brackets arranged upon the bars at the outer ends thereof.

3. In a combined shade and curtain hanger, a pair of bars slidably interconnected, means at the outer ends of the bars for biting engagement with the sides of the window frame, the upper edge of one bar being toothed, a strap member slidable along the toothed bar and having a slot formed in the top thereof, an auxiliary strap disposed above the aforementioned strap and eccentrically pivoted at its lower end to the lower end portion of the first mentioned strap, a dog at the top of the auxiliary strap adapted for movement through the slot formed in the top of the first mentioned strap, 120

the top of the first mentioned strap, whereby said dog may engage the teeth on said bar for locking the straps against sliding movement along the bar, whereby the bars will 5 be initially secured in predetermined adjusted relation, a lever pivotally secured adjacent its lower end on the inner end portion of the other bar, a link connecting the lower end of said lever to the first mentioned 10 strap, said lever and link cooperating with the strap for securing the bars rigidly together in predetermined adjusted relation, and shade brackets arranged on the bars.

4. In a shade bracket of the class described, 15 a bar for attachment to a window frame, said bar being formed with a series of vertically spaced slots, a shade bracket unit slidably arranged upon the bar, said bracket unit comprising a plate, the upper and lower 20 ends thereof being disposed laterally and then inwardly for engagement over the upper and lower edges of the bar, the side portions of the plate being bent laterally and then forwardly to provide a pair of spaced 25 wings, a shade roller supporting bracket plate pivotally secured between said wings, the upper edge of said last-mentioned plate being rounded and adapted to extend through a slot formed in the first mentioned 30 plate and into one of the slots formed in the bar, and a depending finger formed on the

lower inner edge portion of the second mentioned plate to abut the first mentioned plate for limiting the downward swinging movement of the shade roller supporting plates. 35

5. In a shade bracket of the class described, a bar for attachment to a window frame, said bar being formed with a series of vertically spaced slots, a shade bracket unit 40 slidably arranged upon the bar, said bracket unit comprising a plate, the upper and lower ends thereof being disposed laterally and then inwardly for engagement over the upper and lower edges of the bar, the side portions of the plate being bent laterally 45 and then forwardly to provide a pair of spaced wings, a shade roller supporting bracket plate pivotally secured between said wings, the upper edge of said last mentioned plate being rounded and adapted to extend through a slot formed in the first mentioned plate and into one of the slots formed in the bar, and a depending finger formed on the lower inner edge portion of the said second mentioned plate to abut the first mentioned plate for limiting the downward swinging movement of the shade roller supporting plate, and means for holding the wings in frictional engagement with the respective 55 sides of the pivoted plate. 60

In testimony whereof I affix my signature.
PERRY O. LOWERS.
